BOBBIN GATE CONTROL FOR LOOMS

Harry William Thatcher, Mendon, Mass., and Gordon S. Robinson, Woonsocket, R.I., assignors to Draper Corporation, Hopedale, Mass., a corporation of Maine

Filed Feb. 4, 1964, Ser. No. 342,370

8 Claims. (Cl. 139—251)

This invention pertains to looms of the so-called fly shuttle type and is more specifically devoted to an improved means for guiding and presenting filling bobbins for transfer to a loom shuttle.

It is a general object of the invention to provide a bobbin gate control for looms utilizing filling bobbins wound by the direct spun system.

It is a further object to provide a bobbin gate control for restricting the flow of bobbins from a bobbin magazine and for presenting them individually to the bobbin transfer position.

A further object of the invention is to provide a bobbin gate control that can be adjusted to accommodate different sizes of filling packages.

A further and more specific object is to provide a bobbin gate control for maintaining clearance between the bobbin in transfer position and the preceding bobbins being guided from the magazine thereby eliminating the frictional contact therebetween and mitigating the removal of the tailwind and tip bunch during the transfer cycle.

Further objects and advantages of the invention will become apparent from the following more detailed disclosure.

Prior to the instant invention filling bobbins were permitted to travel from the magazine into the guiding chute disposed beneath said magazine by means of gravity, and commencing with the bobbin in transfer position each bobbin was in frictional contact with the filling bobbin preceding it. This manner of guiding and directing the bobbins to that position for transfer into a loom shuttle presented certain undesirable conditions which the device according to the instant invention now prevents.

With the flow of bobbins being controlled by gravity, the frictional contact between the bobbin in transfer position and its predecessor plus the weight of the remaining bobbins in the guiding chute did not permit the tailwind extending from the tip bunch and around the main package to be easily removed with the tip bunch. Under such a condition the tailwind often breaks and the remaining slub is easily carried into the fabric shed resulting in fabric of an inferior quality. This pressure and frictional contact with the bobbin in transfer position are often sufficient so that the tip bunch when being removed by the extractor is pulled out of the extractor jaws resulting in an incomplete transfer; that is to say, the bobbin is transferred into the shuttle but is not threaded through the shuttle eye. A condition of this nature is detected on the first pick of the shuttle by the center fork filling motion resulting in another indication for filling replenishment and the ejection of the unspent bobbin.

The device according to the instant invention has corrected these undesirable conditions described above by providing a bobbin gate control which is adapted to cooperate with the bobbins in the bobbin chute and being mechanically linked to the transferring mechanism, it is timed to restrict the flow of bobbins in the chute during a portion of the transferring cycle and to permit the flow of bobbins in the chute during another portion of said cycle. In effect, the gate control alleviates the removal of the tip bunch and tailwind by maintaining a separation between the bobbin in transfer position and the remaining bobbins in the bobbin chute. Additionally, the gate control func-

2

tions to segregate the bobbin immediately preceding that bobbin in transfer position from the latter bobbin and those remaining in the bobbin chute, and during the transfer cycle it is caused to urge mechanically the segregated bobbin into the proper position for the next filling replenishment indication.

The invention will be described hereinafter in greater detail by reference to the accompanying figures of drawing, in which:

FIG. 1 is a plan view of a portion of the replenishment side of the loom to which the invention has been applied shown broken away and taken generally along line 1—1 in FIG. 2;

FIG. 2 is a view in side elevation and partially in section of many of the parts illustrated in FIG. 1 and showing the relationship of the filling bobbins to the bobbin gate control unit comprising the invention;

FIG. 3 is a view in side elevation of the left-hand bobbin gate member; and

FIG. 4 is a view similar to that of FIG. 2 but showing one of the positions the bobbin gates and follower are caused to assume during the transfer cycle.

Now referring to FIGS. 1, 2, and 4, the invention applies to the filling replenishment side of a loom which includes a bobbin chute generally indicated by numeral 10 disposed beneath a bobbin magazine or hopper (not shown) from which filling bobbins 11 are directed and guided for transfer to a loom shuttle 12. The bobbin chute includes an upper chute member 13 and a lower chute member 14 disposed in spaced relationship to said upper chute member to form a passageway or channel for guiding the filling bobbins therebetween.

A bobbin 11 when in transfer position (FIG. 2) is supported in a known manner by a bobbin guide 15, a pivotable bobbin support 16, and a spring biased top holder (not shown) which is adapted to guide the tip portion of said bobbin.

The transerrer generally indicated by numeral 17 in FIG. 1 having a transerrer head shaft 18 also functions in a known manner to replenish a loom shuttle with a new bobbin and to eject the spent bobbin therefrom.

As the general construction and operation of this type of loom is well known and familiar to those conversant with the art, and as the invention is entirely concerned with the bobbin chute gate control, it is only considered necessary here to illustrate and describe those parts of a loom directly concerned with a preferred form of the present invention.

The device according to the instant invention includes a bobbin gate bracket member indicated generally by numeral 19 having a main body portion 20 which is attached to the upper chute member 13 by means of cap screws 21 and 22. The forward end of the main body portion 20 is provided with an integrally formed and downwardly directed arcuated finger 23 which terminates in the form of a hub 24. A bobbin gate shaft 25 is journaled in hub 24 and extending from each side thereof it is provided with aligned right- and left-hand bobbin gates, each by numeral 27. These bobbin gates are fixedly attached to the gate shaft 25 by means of set screws 28 and 29, respectively, and are movable simultaneously in a manner to be more fully described hereinafter.

Hub 24 is provided with an extended neck portion 30 on which a torsion type spring 31 is adapted to assemble. The ends of spring 31 are directed at an angle substantially perpendicular to its coils with one end thereof being seated in an aperture provided in finger 23 immediately above the hub 24. The opposite end of this spring is seated in an appropriate aperture provided on the inner side of the right-hand bobbin gate 26 and being assembled in this manner, both the right- and left-hand bobbin gates are continually urged in an anti-clockwise direction as

seen looking from the right-hand side of the loom (FIG. 2).

The main body portion 20 of the bobbin gate bracket 19 is provided with a centrally disposed and downwardly directed lug member 32 positioned rearwardly of the arcuated finger 23 and is integrally formed with said main body portion. This lug member serves to support a generally U-shaped bobbin gate follower 33 which is mechanically linked to and adapted to cooperate with the bobbin gates 26 and 27. The bobbin gate follower 33 is pivotally supported by means of a shaft member 34 which is fixedly positioned in the lug member 32 by means of a set screw 35. The ends of the shaft member 34 extending outwardly from each side of the lug member 32 are adapted to assemble in aligned and centrally disposed apertures provided in the leg portions 36 and 37 of the bobbin gate follower 33 (FIG. 1).

A bobbin gate follower shaft 38 assembles in aligned apertures provided in the forward ends of the leg portions 36 and 37 of the bobbin gate follower 33 and the ends of said shaft extending outwardly from each side of said leg portions are slidably received into aligned channels or recesses 39 and 40 provided on the upper and inner side of the right- and left-hand bobbin gates 26 and 27, respectively. The bobbin gates 26 and 27 being mechanically linked to the bobbin gate follower 33 in this manner cause the latter to pivot in a clockwise direction when the gate members are caused to pivot in an anti-clockwise direction and then in the opposite direction when said gate members are caused to be moved in a clockwise direction.

The bobbin gates 26 and 27 are caused to pivot first in one direction and then the other by means of the transferred head shaft 18. As shown in FIGS. 1 and 2 the right-hand bobbin gate 26 is provided at its forward end with a bifurcated portion 41 through which the transerrer head shaft 18 is caused to extend.

In operation, a bobbin 11 is in transfer position as shown at the lower left in FIG. 2 and when an indication is given for filling replenishment, the transerrer head shaft 18 is forced downwardly in a known manner as shown in FIG. 4 to transfer that bobbin into the shuttle 12 and to eject the spent bobbin therefrom. Movement of the transerrer head shaft 18 from that position depicted in FIG. 2 to that position shown in FIG. 4 causes the bobbin gates 26 and 27 to pivot in an anti-clockwise direction causing the bobbin gate follower 33 to move in a clockwise direction.

Movement of the bobbin gate follower in this manner pushes a first or the next bobbin to a position between said follower and the bobbin gates as shown in FIG. 4.

During the return of the transerrer head shaft 18 to its initial position, the shaft enters the bifurcated portion 41 of the right-hand bobbin gate 26 causing the latter and the left-hand bobbin gate 27 to pivot in a clockwise direction. This movement brings the heel portions 42 and 43 of the bobbin gates 26 and 27, respectively, into contact with the first filling bobbin urging the latter into transfer position. At this time the bobbin gate follower is moving in an anti-clockwise direction and after having moved the limit of its travel, sufficient clearance is provided to allow the next or second bobbin in the bobbin chute to roll into that position depicted in FIG. 2 underneath the gate follower.

The bobbin gate control is adjustable to accommodate bobbins having filling packages of different diameters. To accomplish this adjustability, shaft member 34 is provided with a fixedly positioned and centrally disposed bushing 44 which is journaled in the lug member 32. Shaft member 34 is eccentrically poositioned in bushing 44 and is provided with a screw driver slot 45 on the outer end thereof. By loosening set screw 35 and then turning shaft member 34 in one direction or the other, the bobbin gate follower 33 can be raised or lowered slightly to provide clearance for the size filling package

being utilized. Retightening of set screw 35 maintains the follower 33 in the desired operating position.

While one embodiment of the invention has been disclosed, it is to be understood that the inventive concept 5 may be carried out in a number of ways. This invention is, therefore, not to be limited to the precise details described, but is intended to embrace all variations and modifications thereof falling within the spirit of the invention and the scope of the claims.

We claim:

- 10 1. In a loom for weaving having a filling hopper for retaining a supply of filling bobbins and a bobbin chute adapted to receive and guide the bobbins from said hopper to present them for transfer to a loom shuttle, a bobbin chute gate control including a pivotable gate member for alternately restricting and permitting the passage of bobbins in said bobbin chute, and for urging a bobbin into transfer position, a pivotable gate follower associated with said gate member for initially urging said bobbin to a position to be acted upon by said gate member.
- 15 2. In a loom for weaving having a filling hopper for retaining a supply of filling bobbins and a bobbin chute adapted to receive and guide the bobbins from said hopper to present them for transfer to a loom shuttle, a bobbin chute gate control including axially aligned and remotely disposed right- and left-hand bobbin gate members 25 movable simultaneously for restricting and permitting the passage of bobbins in said bobbin chute, and for urging a bobbin into transfer position, a pivotable gate follower associated with said gate member for initially urging said bobbin to a position to be acted upon by said gate member.
- 30 3. In a loom for weaving having a filling hopper for retaining a supply of filling bobbins and a bobbin chute adapted to receive and guide the bobbins from said hopper to present them for transfer to a loom shuttle, a bobbin chute gate control including a pivotable gate member for alternately restricting and permitting the passage of bobbins in said bobbin chute, and for urging a bobbin into transfer position, a pivotable gate follower 35 associated with said gate member for initially urging said bobbin to a position to be acted upon by said gate member, said gate follower being eccentrically adjustable to accommodate different sizes of filling packages.
- 35 4. For use in a loom for weaving having a filling hopper for retaining a supply of filling bobbins and a bobbin chute adapted to receive and guide the bobbins from said hopper to present them for transfer to a loom shuttle, a bobbin chute gate control including a pivotable gate member for restricting and permitting the passage of bobbins in said bobbin chute, and for urging a bobbin into transfer position, a pivotable bobbin gate follower 50 disposed intermediate said gate members and mechanically linked thereto for initially urging said bobbin to a position to be acted upon by said right- and left-hand gate members.
- 40 5. For use in a loom for weaving having a filling hopper for retaining a supply of filling bobbins and a bobbin chute adapted to receive and guide the bobbins from said hopper to present them for transfer to a loom shuttle, a bobbin chute gate control including a pivotable gate member for alternately restricting and permitting the passage of bobbins in said bobbin chute, and for urging a bobbin into transfer position, a pivotable bobbin gate follower 55 disposed intermediate said gate members and mechanically linked thereto for initially urging said bobbin to a position to be acted upon by said right- and left-hand gate members.
- 50 6. For use in a loom for weaving having a filling hopper for retaining a supply of filling bobbins and a bobbin chute adapted to receive and guide the bobbins from said hopper to present them for transfer to a loom shuttle, a bobbin chute gate control including axially aligned and remotely disposed right- and left-hand bobbin gate members 60 movable simultaneously for restricting and permitting the passage of bobbins in said bobbin chute, and for urging a bobbin into transfer position, a pivotable bobbin gate follower disposed intermediate said gate members and mechanically linked thereto for initially urging said bobbin to a position to be acted upon by said right- and left-hand gate members.
- 65 7. For use in a loom for weaving having a filling hopper for retaining a supply of filling bobbins and a bobbin chute adapted to receive and guide the bobbins from said hopper to present them for transfer to a loom shuttle, a bobbin chute gate control including a pivotable gate member for alternately restricting and permitting the passage of bobbins in said bobbin chute, and for urging a bobbin into transfer position, a pivotable bobbin gate follower 70 disposed intermediate said gate members and mechanically linked thereto for initially urging said bobbin to a position to be acted upon by said right- and left-hand gate members.
- 75 8. For use in a loom for weaving having a filling hopper for retaining a supply of filling bobbins and a bobbin chute adapted to receive and guide the bobbins from said hopper to present them for transfer to a loom shuttle,

a bobbin chute gate control including a pivotable gate member for restricting and permitting the passage of bobbins in said bobbin chute, and for urging a bobbin into transfer position, a pivotable bobbin gate follower disposed intermediate said gate members and mechanically linked thereto for initially urging said bobbin to a position to be acted upon by said right- and left-hand gate members, said pivotable gate follower being eccentrically adjustable to accommodate different sizes of filling packages.

7. In a loom for weaving having a filling hopper for retaining a supply of filling bobbins and a bobbin chute adapted to receive and guide the bobbins from said hopper to present them for transfer to a loom shuttle, a bobbin chute gate control including a pivotable means adapted upon the initial movement thereof to restrict the flow of bobbins in said chute and to urge an individual bobbin to a position intermediate said pivotable means and transfer position and further adapted upon the return movement of said pivotable means to urge said individual bobbin to transfer position.

8. For use in a loom for weaving having a filling hop-

per for retaining a supply of filling bobbins and a bobbin chute adapted to receive and guide the bobbins from said hopper to present them for transfer to a loom shuttle, a bobbin chute gate control including dual co-acting pivotable means adapted upon the initial movement thereof to restrict the flow of bobbins in said chute and to urge an individual bobbin to a position intermediate said pivotable means and transfer position and further adapted upon the return movement of said pivotable means to urge said individual bobbin to transfer position.
